US00D664515S

(12) **United States Design Patent**
Fagnot et al.

(10) **Patent No.:** US D664,515 S
(45) **Date of Patent:** ** Jul. 31, 2012

(54) **MOBILE PHONE**

(75) Inventors: **Benjamin Fagnot**, Lund (SE); **Shinsaku Hirano**, Lund (SE); **Bilgi Karan**, Lund (SE)

(73) Assignee: **Sony Mobile Communications AB**, Lund (SE)

(**) Term: **14 Years**

(21) Appl. No.: **29/388,886**

(22) Filed: **Apr. 4, 2011**

(30) **Foreign Application Priority Data**

Nov. 10, 2010 (EM) 001244107-0001

(51) **LOC (9) Cl.** **14-03**

(52) **U.S. Cl.** ..... **D14/138 G**

(58) **Field of Classification Search** ..... D14/138 R, D14/138 AD, 138 AC, 138 C, 138 G, 191, D14/203.1–203.8, 496, 138 AA, 138 AB, D14/137, 147, 218, 341–347, 247–248; D10/65, D10/78, 104; D13/168; D18/7; 455/566, 455/575.1, 575.3, 575.4

See application file for complete search history.
